UNITED STATES PATENT OFFICE.

ABTON ALBERT BUCK, OF ZURICH, SWITZERLAND.

ROTARY ELECTRIC SWITCH.

1,394,515.

Specification of Letters Patent. Patented Oct. 18, 1921.

Application filed August 6, 1917, Serial No. 184,782. Renewed March 2, 1921. Serial No. 449,272.

(GRANTED UNDER THE PROVISIONS OF THE ACT OF MARCH 3, 1921, 41 STAT. L., 1313.)

To all whom it may concern:

Be it known that I, ABTON ALBERT BUCK, a citizen of the Swiss Confederation, residing at Zurich, Canton Zurich, Switzerland, 5 have invented new and useful Improvements in Rotary Electric Switches, of which the following is a specification.

This invention relates to a form of rotary electric switch for switching in and out two electric resistances particularly for use of regulating the heating effect on electric heating-cushions, heating-carpets, heating bandages and so forth, and it comprises a turnable ring or annular switch member 10 fitted with two screwed diametrically positioned contacts which connect up the pin-contacts of a central switch block with the leading-in and the return conductors.

The accompanying drawings show the invention in a form of construction serving as an example, in which:—

Figure 1 is an axial section of the switch; Fig. 2, a cross-section taken on the line A—B of Fig. 1; Figs. 3, 4, 5 and 6 are diagrams showing various positions of the contacts.

The switch consists of the central switch-block *f* which is firmly lodged in two shells *g* which protect the conductors, and between 30 which is turnably held a ring or annular switch member *a*. The member *a* carries two diametrically placed contacts *b* consisting each of two tubes, the one part *h* of which may be externally screw-threaded so as to 35 be made fast in the ring *a*, while the other tube *i* loosely engages in the tube *h* so as to slide endwise. The inner tube *i* is closed at its inner end but open at the opposite end. The tube *h* can be closed externally by a cap 40 after the introduction of a spring *c* which tends to push the tube *i* forward against the sides of any two adjacent contact pins *d* fast in the block *f*. By way of an example I have shown eight contact pins *d* marked I, II to 45 VIII on the drawing. One of the pins, for example, I, is connected with the positive pole of an electric source of supply while the negative pole of same is connected with the pin IV. Further, the pin I is connected 50 with an electric resistance *W*¹ and a resistance *W*² is connected with the pin-contact VII. The two resistances are electrically connected with each other and from this connection of the two resistances there leads 55 an electric connection to the pin-contact V. Moreover, the contact VII is connected with

the contact VIII, and the contact IV is connected with the contact VI.

The action is as follows:

In turning the ring *a* on the block *f*, the 60 springs *c* insure against unintentional shifting of the ring *a*. Fig. 3 shows the position of the ring *a* in which the contacts *b* connect with each other the contacts VII and VIII on the one hand, and the contacts III and 65 IV on the other hand. With this position no current passes through the resistances *W*¹ and *W*² so that the heating device is switched off. Fig. 4 shows the contacts *b* in position connecting the contact II with III 70 and contact VI with VII, whereby the resistances *W*¹ and *W*² are connected in series. Consequently the positive current passes from contact I through the resistance *W*¹ and then in series through the resistance *W*² 75 on to the contacts VII, VI and IV, and off through the return wire, so that "low" heating effect is obtained. Fig. 5 shows the switch in position to pass the positive current through I, *W*¹, V, VI and IV, into the return wire so insuring the single effect of resistance *W*¹ and a "mean" heating effect. Fig. 6, as in Fig. 2, shows the resistances *W*¹ and *W*² in parallel across the positive and negative wires and the current will 80 pass over the contact I to the resistance *W*¹ and over the contacts VIII and VII to the resistance *W*², and from the two resistances it will pass through contacts V and IV to the negative wire back to battery. This position insures "full" heating effect. 90

The advantages of this switch-device consist in that the jamming of any of its parts is prevented; that the switch may be turned both ways without damage; and that the 95 twisting of the leading-in and leading-off wires is impossible.

Having described my invention, I claim:

A rotary electric switch for connecting up 100 two electric resistances, which consists in the combination of a transversely divided cylindrical shell, a concentric block fixed in said shell, a plurality of cylindrical longitudinally disposed pin contacts carried in a circular line in said block, an annular disk 105 turnably engaged between and projecting concentrically from the periphery of said shell, and diametral spring-tube contacts secured in the annular disk for automatic engagement and disengagement between any 110 two of said cylindrical pin contacts.

ABTON ALBERT BUCK.
